Application January 1, 1943, Serial No. 471,037

16 Claims. (Cl. 58—24)

1

My invention relates to time keeping apparatus and more particularly to clocks and clock systems; for example, a clock system wherein one or more secondary clocks which are operated during normal operating periods at their regular time rates, are periodically regulated to correct, if necessary, their respective time settings in accordance with a selected standard time setting such, for example, as a master clock continuously operated at the correct time rate.

An object of the invention is to provide apparatus of the above type which is of improved construction and arrangement of parts, and one which is simple in its construction and which is reliable and effective in its operation.

In accordance with one aspect of the present invention, I provide apparatus of the above type comprising a time indicating element such as a minutes indicating member; a driving motor, such for example as a synchronous motor operated at a regular time rate from a commercial alternating current power line; and a motion-transmitting mechanism connecting the motor with the minutes member. The apparatus also comprises a control means which causes the motor to drive the minutes member through the motion transmitting mechanism at its normal or regular rate during normal operating periods of fixed and relatively long durations, for example, from the beginning of each hour to the fifty-ninth minute, and which also causes the motor to drive the minutes member through the mechanism at a greatly accelerated rate during a synchronizing period occurring between successive normal operating periods, and until the minutes member occupies a preselected time position, for example, the zero or sixtieth minute position which is the position the member should occupy at the beginning of the next normal operating period. The control means operates to stop the minutes member upon reaching this preselected time position, and releases the minutes member at the beginning of the next normal operating period, so that the setting of the minutes member will be correct at the beginning of each normal operating period.

A further object of my invention is to provide a new and improved clock for use in systems of the type referred to above, which clock comprises a novel means for periodically correcting the time setting thereof in accordance with a selected standard time setting.

A still further object is to provide a clock of the above type including new and improved motion transmitting mechanism which is controlled by a signal responsive means to operate the

2

time indicating member from a driving motor at the regular time rate during normal operating periods and to operate the time indicating member from the same motor at a greatly accelerated time rate during synchronizing periods.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a fragmentary vertical section showing one preferred form of secondary clock constructed in accordance with the present invention, the plane of the section being indicated by the line 1—1 of Fig. 2, and the view showing the relative positions of the parts at the end of a synchronizing period;

Fig. 2 is a fragmentary end elevation of the clock shown in Fig. 1;

Fig. 3 is an enlarged fragmentary vertical section taken on the line 3—3 of Fig. 1;

Fig. 4 is an enlarged fragmentary plan section taken on the line 4—4 of Fig. 1.

Fig. 5 is a fragmentary sectional view in the same plane as Fig. 1 and showing the relation of the parts at the beginning of a synchronizing period;

Fig. 6 is a view like Fig. 5 and showing the relation of the parts during a normal operating period.

Fig. 7 is a wiring diagram illustrating how a plurality of secondary clocks like the one of Figs. 1 to 6, inclusive, may be connected for operation by a source of alternating current and how the operation of the secondary clocks may be controlled by a master clock;

Fig. 8 is a fragmentary sectional view like Fig. 1 and showing a modified form of secondary clock constructed in accordance with the present invention;

Fig. 9 is a fragmentary end elevation like Fig. 2 and showing the same clock as Fig. 8;

Fig. 10 is a fragmentary vertical section taken on the line 10—10 of Fig. 8;

Fig. 11 is an enlarged fragmentary plan section on the line 11—11 of Fig. 8;

Fig. 12 is a wiring diagram showing an alternative way of controlling the operation of a plurality of secondary clocks by a master clock;

Fig. 13 is a fragmentary sectional view like Figs. 1 and 8 and illustrating another modified form of secondary clock constructed in accordance with the present invention;

Fig. 14 is a fragmentary end view like Figs. 2 and 9 and illustrating the modification of Fig. 13;

Fig. 15 is an enlarged fragmentary plan section taken on the line 15—15 of Fig. 13;

Fig. 16 is a fragmentary detail sectional view showing more clearly the relationship of certain of the parts shown in Figs. 13, 14, and 15; and

Fig. 17 is a wiring diagram illustrating how a plurality of secondary clocks like the one shown in Figs. 13 to 16, inclusive, may be controlled by a master clock.

Referring now in detail to the construction illustrated and first to Figs. 1 to 6 inclusive, the reference numeral 10 indicates, in its entirety, one preferred form of secondary clock constructed in accordance with the present invention. The clock 10 comprises the customary face plate 11, back support plate 12 and an intermediate support plate 13 suitably secured together in fixed parallel relation by the usual pillars 14. A self-starting synchronous motor 15 is supported by the back plate 12 and is driven at a substantially uniform time rate from the available alternating current light and power line. The synchronous motor includes a shaft 16 extending through an opening in the back plate and to the outer end of the shaft 16 is fixed a small driving pinion or gear 17.

The motor 15 drives a seconds arbor or shaft 20 by means of the gear 17 meshing with a large spur gear 21 which is fixed to a collar 22 keyed to the shaft 20. The gears 17 and 21 are of such a size with respect to the speed of the motor shaft 16, that they drive the seconds shaft 20 at the normal or regular time rate of one revolution per minute. The usual seconds hand 24 is fixed to the outer end of the shaft 20 (see Fig. 3). The seconds shaft is rotatably supported at its inner end by the back support plate 12 and is also rotatably supported by a minutes sleeve 25 journaled on said shaft and in turn supported for rotary movement about its axis and the axis of the shaft 20, by the intermediate support plate 13 and by the hour sleeve 26, the latter being in turn supported by the face plate 11. The minutes hand 27 is fixed to the outer end of the sleeve 25 and the hour hand 28 to the outer end of the sleeve 26. The hours sleeve 26 is driven from the minutes sleeve through the conventional gear train composed of gears 29, 30, 31 and 32.

In accordance with the present invention, I provide a planetary gear system for driving the minutes sleeve 25 during normal operating periods at the regular time rate with respect to the seconds shaft 20. The gear system comprises a planet arm 34 fixed to the collar 22 and thereby rotating about the axis of the seconds shaft at the same rate as said shaft. The planet arm 34 carries at its outer end a planet pinion 35 rotatably mounted upon a sleeve 36 which is in turn journaled on a stud 37 fixed to the arm 34. The planetary gear system also comprises a pair of sun gears 38 and 39, respectively, which are mounted for rotation about the same axis as the arm 34 and are both in mesh with the planet pinion. The sun gear 38 is fixed to the inner end of the minutes sleeve 25 and the other sun gear 39 is fixed to one end of a sleeve 40 rotatably mounted on the minutes sleeve 25. As will appear presently, the sun gear 39 is held stationary during normal operating periods. The sun gears 38 and 39 have the same pitch diameter and the number of teeth on the sun

gear 38 is so proportioned to the number of teeth on the gear 39 that with the sun gear 39 held stationary and the planet arm 34 rotated for one complete revolution, the sun gear 38 and the minutes sleeve 25 will be advanced one-sixtieth of a revolution. In the construction shown, the normally stationary sun gear 39 is provided with fifty-nine teeth and the sun gear 38 which is fixed to the minutes sleeve is provided with sixty teeth. Thus, for each rotation of the planet arm the sun gear 38 is advanced one tooth, or one sixtieth of a revolution. It will be of interest to note that during normal operating periods, the rate and direction of rotation of the pinion 35 about its own axis are controlled by the stationary sun gear 39 and by the rate and direction of rotation of the planet arm.

Fixed to the end of the sleeve 40 which is opposite the sun gear 39, is a relatively large diameter circular disk 42 having teeth 43 cut on its outer periphery. During normal operating periods a tooth-like projection 44 on the outer end of an arm 45 of a lever 46 engages between two of the teeth 43 on the periphery of the disk 42 and thereby holds the disk 42, sleeve 40 and sun gear 39 against rotation. The lever 46 is rotatably supported by a fulcrum shaft 47 which is in turn supported by the plates 12 and 13, and the projection 44 is held in locking engagement with the disk 42 by a tension spring 48 connected at one end to the lower end of the arm 45 and its other end to the lower end of an arm 49 of an operating lever 50 also journaled on the shaft 47.

Summarizing the foregoing, it is noted that with the synchronous motor operated from the available commercial alternating current supply at its designed regular time rate, the seconds shaft 20 will be rotated at the rate of one revolution per minute; and, with the fifty-nine tooth sun gear 39 held stationary, the minutes sleeve 25 will be rotated at the rate of one sixtieth of a revolution per minute through the planetary gear system, and the hour sleeve 26 will be driven from the minutes sleeve at the regular time rate through the train of reduction gears 29, 30, 31, and 32, respectively. Ordinarily, the secondary clock 10 operates at the correct time rate due to the controlled frequency of the commercial alternating current supply. As is well known, however, it is necessary to provide for periodically correcting the time settings of secondary clocks, because of occasional stoppage of the current supply or due to possible excess friction in the motion transmitting mechanism of one or more of the secondary clocks, or due to other causes well known to those skilled in this art.

According to this invention, provision is made for operating the secondary clock at the above-described regular rate during each normal operating period which, in the embodiment disclosed, extends for the greater part of each hour; for example, from the beginning of each hour until fifty-nine minutes past the hour. Also, provision is made for operating the clock at a greatly accelerated rate during synchronizing periods of relatively short duration, for the purpose of correcting for any loss in time. The synchronizing periods occur between successive normal operating periods and in the example disclosed the synchronizing period is the one minute interval between the fifty-ninth minute and the sixtieth minute or zero time position. The clock starts operating at the fast rate at the beginning of the sixtieth minute and continues until the minutes

and seconds indicating members reach a preselected position indicating the end of the sixtieth minute or the beginning of the next hour. At this point the minutes and seconds members are stopped and held stationary. At the beginning of the next hour the two time indicating members are released by a time signal from a master clock, thus starting the secondary clock off at the correct time.

In the construction shown in Figs. 1 to 6, inclusive, the minutes sleeve 25 and hand 27 of the secondary clock 10 operate at a greatly accelerated rate during synchronizing periods due to the releasing of the fifty-nine tooth sun gear 39 and by controlling the rotation of the planet pinion 35 about its rotary axis. The sun gear 39 is released by moving the lever arm 45 clockwise to disengage the tooth-like projection 44 from the periphery of the disk 42 in a manner which will be presently described. The planet pinion 35 is controlled in its rotation about its rotary axis during synchronizing periods due to its frictional driving connection with a relatively large gear 55 which meshes with a second and relatively small gear 56 coaxially mounted with the sun gears 38 and 39 and held stationary during each synchronizing period.

The gear 55 is fixed to the sleeve 36 and is frictionally connected to the side of the pinion 35 by a spider-like spring member 57 engaging the side of the pinion and urging the latter toward the gear 55, and by a disk of suitable friction material 58 positioned between the pinion and gear to assure frictional engagement of the parts. The gear 56 which is held stationary during synchronizing periods is fixed to a sleeve 60 journaled on the outer cylindrical surfaces of the sleeve 40. A circular disk 61 of substantially the same diameter as the disk 42 is fixed to the sleeve 60 and is also provided on its periphery with teeth 62 which are adapted to be engaged and held stationary during synchronizing periods by a tooth-like projection 63 carried on the outer end of a second arm 64 of the lever 46.

The lever 46 is rocked counterclockwise, in a manner which will be presently explained, at the beginning of a normal operating period to effect locking engagement of the projection 44 and disk 42 and to effect disengagement of the projection 63 and disk 61, and the lever 46 is rocked clockwise at the beginning of a synchronizing period to effect disengagement of the projection 44 and disk 42 and engagement of the projection 63 and disk 61. Thus, during normal operating periods, the sun gear 39 is held against rotation and the gear 56 freely rotates with the pinion 35 under the control of the stationary sun gear; and, during synchronizing periods, the gear 56 is held against rotation to control rotation of the pinion about its axis and the sun gear 39 is permitted to freely rotate.

In the construction shown, the planet pinion 35 has thirty-six teeth. The gear 55 which is frictionally connected with the planet pinion has sixty teeth, and the gear 56 which meshes with the gear 55 and is held stationary during synchronizing periods, has thirty-six teeth. Thus, during synchronizing periods with the arm 34 rotated at the speed of the second shaft and with the sun gear 39 released, for each revolution of the arm 34, thirty-six teeth of the gear 55 will mesh with the gear 56. Consequently, the gear 55 is rotated $3\frac{1}{2}\%$ of a revolution in a clockwise direction; and, as the gear 55 and pinion 35 are frictionally connected, the pinion 35 is also ro-

tated $3\frac{1}{2}\%$ of a revolution. $3\frac{1}{2}\%$ of a revolution of the thirty-six tooth pinion 35 is equivalent to 21.6 teeth on such pinion. Therefore, for each revolution of the arm 34 the sun gear 38 is rotated an amount equal to 21.6 teeth in a counterclockwise direction; but, as the planet arm has been rotated clockwise one complete revolution, the resultant movement of the sixty tooth sun gear 38 will be sixty teeth clockwise minus 21.6 teeth counterclockwise or 38.4 teeth clockwise. This equals $38\frac{4}{5}\%$ of a revolution for each revolution of the planet arm. As the sun gear 38 only rotates one tooth or $\frac{1}{60}$ of a revolution for each revolution of the planet arm during normal operating periods, it follows that the sun gear 38 will be driven 38.4 times as fast during synchronizing periods. This greatly accelerated rate of rotation during the one minute synchronizing period makes possible the maximum advancement of 38.4 minutes of the minute sleeve 25. This is considered ample for any ordinary condition that might arise. If a greater time correction is required, it can be effected during succeeding synchronizing periods. It will be appreciated, of course, that a greater or lesser amount of correction in a given synchronizing period can be easily provided by varying the relative sizes of the gears 55 and 56.

The lever 46 is moved in directions to effect locking and releasing of the two disks 42 and 61 due to the operative engagement of a pin 66 on the downwardly extending arm 49 of the operating lever 50, with a third arm 67 on the lever 46. The operating lever 50 also includes an upstanding arm 68 having a vertical slot 69 formed therein and receiving a pin 70 carried by the lower end of a lever arm 71. The arm 71 is secured intermediate its ends by a pin 72 to the armature 73 of a solenoid 74 and the upper end of the arm 71 is pivoted to a pin 75 on a fixed supporting element 76 carried by the solenoid 74. As will presently appear, the solenoid 74 is energized by the flow of direct current thereto under the control of a master clock, at the beginning of each synchronizing period and is deenergized under the control of such master clock at the end of the synchronizing period. When the solenoid is energized, at the beginning of each synchronizing period, the armature 73 moves to the right as viewed in Fig. 1 and moves with it the arm 71 which in turn moves the operating lever 50 clockwise about the fulcrum shaft 47 to effect operative engagement of the pin 66 and arm 67 and thereby rock the lever 46 clockwise to disengage the disk 42 and engage the disk 61 in the manner previously explained. When the solenoid is deenergized at the end of the synchronizing period, a tension spring 77 connected at one end to the lower end of arm 49 and at its other end to a fixed stud 78, moves the lever 50 counterclockwise and the armature 73 to the left, as viewed in Fig. 1 and thus permits the spring 77 to move the lever 46 counterclockwise to lock the disk 42 and disengage the disk 61.

As stated above, I also provide a means which acts during synchronizing periods to stop the minutes sleeve when it reaches a preselected time position corresponding to the beginning of the next normal operating period and for holding the sleeve in this position until the beginning of the next succeeding normal operating period when it is released so that it can operate at its regular or normal time rate as before. As stated, this preselected time position is preferably the zero or sixtieth minute position. In the construction 75 shown, this stop means comprises a relatively

large circular disk 80 which is fixed to a sleeve 81 in turn fixed to the minutes sleeve 25 so that it will rotate with the minutes sleeve, and the disk 80 is provided on its periphery with a single notch 82 adapted to be engaged by a tooth-like projection 83 on a lever arm 84 when the disk 80 reaches a position corresponding to the position of the sleeve 25 and hand 27 should correctly occupy at the sixtieth minute. The lever arm 84 is also fulcrumed on the shaft 47 and is held out of engagement with the disk 80 during normal operating periods when the solenoid is deenergized, by means of the pin 66 on the operating lever 50. As stated before, at the beginning of the synchronizing period the solenoid is energized to move the operating lever and pin clockwise to release the disk 42 and stop the disk 61. The clockwise movement of the pin 66 permits the lever arm 84 also to be moved clockwise by a tension spring 85 connecting the ends of arm 49 and arm 84, and thereby to effect engagement of the projection 83 with the periphery of the disk 80. Figure 6 shows the pin 66 engaging the underside of the lever arm 84 and holding the projection 83 out of engagement with the disk 80, which is the position occupied during normal operating periods. Figure 5 shows the position of the parts during a synchronizing period when the arm 84 has been released so that it is in engagement with the rim of the disk 80 and before it has entered the notch 82 to stop the disk 80 and the minutes sleeve 25. Figure 1 shows the projection 83 in the notch 82 which is the position of the parts when the minutes sleeve 25 and disk 80 are in the preselected sixty minute position.

The aforementioned stop means also preferably includes a means for stopping the seconds shaft 28, after the minutes sleeve has been stopped in the manner just described, at the zero or sixty second position of the seconds hand, so that the seconds hand as well as the minutes hand will start off at the correct time setting at the beginning of the next normal operating period. To this end, the lever arm 84 is rigidly connected by an integral plate 86 with an arm 87 carrying a pin 88 which fits within a horizontal slot 89 in an arm 90 also fulcrumed on the shaft 47. A tension spring 91 connecting upstanding arms 92 and 93 on the lever arms 90 and 87, respectively, constantly urges the arms 92 and 93 in a direction where the pin 88 normally engages the upper edge of the slot 89. The arm 90 is provided with a downwardly extending tooth-like projection 94 which when the projection 83 enters the notch 82 is moved into the path of the upper end of the planet arm 34 and will stop the same and the seconds shaft 28, at the zero or sixty second position, which is the position of the parts just described in Figs. 1, 2, 3 and 4. The construction is such that when the projection 83 is down and in engagement with the rim of the disk 80 and before it enters the notch 82 like in Fig. 5, the projection 94 is out of the path of the planet arm 34 so that the latter is free to rotate until the projection 83 enters the notch 82 to hold the minutes member 25 at the sixty minute position.

In Figure 7 of the drawings there is shown a wiring diagram which illustrates one preferred manner of supplying a commercial alternating current to the motors 15 of a plurality of secondary clocks like the clock 10 of Figures 1 to 6, inclusive, for the purpose of operating the clocks at the desired regular time rate, and which also illustrates how the flow of a direct current to the solenoids

74 of the clocks 10 may be controlled by a master clock operating at the correct time rate, so as to determine the time of beginning and ending of the normal operating periods and the synchronizing periods. The contacts 95 and 96 are a part of the master clock of any suitable construction known to those skilled in the clock art, and are operated so that the contacts 95 open and the contacts 96 close at the end of each synchronizing period, which is also the beginning of the succeeding normal operating period, and so that the contacts 95 close and the contacts 96 open at the end of each normal operating period which is also the beginning of the succeeding synchronizing period. As stated previously, in the embodiment disclosed the normal operating periods are selected to begin on the hour and continue until fifty-nine minutes past the hour, and the synchronizing periods begin at fifty-nine minutes past the hour and end on the hour or at each sixty minute or zero position of the clock 10. Thus, the contacts 95 will be opened and the contacts 96 closed by the master clock at the beginning of each hour and the contacts 95 will be closed and the contacts 96 opened at fifty-nine minutes past each hour.

In the diagram, 97 indicates a suitable transformer having its primary connected to the usual commercial alternating current power and light line indicated by the terminals 98 and 99. At the beginning of each normal operating period with the contacts 95 closed, AC current will flow from the secondary 100 through the wire 101, wire 102, contacts 93, wire 103, wire 104, and wires 105 connected in parallel, to the several motors 15; and, from the motors 15, through condensers 106, and wires 107, 108 and 109, back to the secondary 100. The impedance of the coils of the solenoids 74 is high enough so that the A. C. current flow just described will not effect the armatures of these solenoids. As the contacts 95 are open during the fifty-nine minute normal operating periods, current will not flow from the secondary 100.

At the beginning of and during each synchronizing period with the contacts 95 closed and the contacts 69 open, and A. C. current will flow as before from one side of the secondary 100 and through the wire 101 and wire 102, but, as the contacts 66 are open, the A. C. current will flow through the wire 111 and condenser 112 instead, and will then flow as before through the wires 104 and 105 to the motors 15 and back through the wires 107, 108, and 109 to the other side of the secondary 100. With the contacts 95 closed, the two input terminals 113 and 114 of a conventional full-wave dry-plate rectifier 115 are connected across the secondary 110 by the wire 116 and by the wire 117 and contacts 95. A D. C. current will then flow from one output terminal 118 of the rectifier through a wire 119, wire 104, wires 105 connected in parallel to the coils of the solenoids 74; and the D. C. current will flow from the solenoids 74 through the wires 107, wires 108 and 109, secondary 100, wire 101, and wire 120, to the other output terminal 121 of the rectifier 115. From the above it is apparent that I have provided a simple and novel two wire system for operating one or more secondary clocks 10 from the customary outlet of the usual lighting current. The D. C. current for energizing the solenoids is superimposed on the A. C. current operating the secondary clock motors. The condenser 112 and wire 111 provide a path for the A. C. current without shorting the rectifier 115 during synchronizing.

periods, and the condensers 106 prevent the flow of the D. C. current through the motors 15.

In Figs. 8 to 11, inclusive, I have shown a modified form of secondary clock 10a constructed in accordance with the present invention. The clock 10a is similar in many respects to the clock 10 disclosed in Figs. 1 to 6, inclusive. As will presently appear, the principal difference between the construction of clocks 10a and 10 is in the provision for controlling the operation of the planet pinion during synchronizing periods to drive the minute sleeve at the greatly accelerated rate.

Like the previous modification, the clock 10a comprises a face plate 11a, intermediate support plate 13a, and back plate 12a suitably secured together in fixed spaced relation, and a synchronous motor 15a carried by the back plate 12a and driving through spur gears 17a and 21a, and sleeve 22a, a seconds arbor or shaft 20a. The inner end of the seconds shaft is journaled in the back plate 12a and is supported by a minutes sleeve 25a journaled on the outer surface of the shaft 20a and by an hours sleeve 26a journaled on the minutes sleeve 25a and in turn rotatably supported within an opening in the face plate 11a. The intermediate portions of the minutes sleeve 25a are journaled within the bore of a spacing collar 125 fixed within an opening in the intermediate support plate 13a.

Also, like the previous modification, a planet arm 34a is fixed to the collar 22a and gear 21a and rotates therewith at the speed of the seconds shaft 20a. The planet arm carries on its outer end, a planet pinion 35a rotatably mounted upon a fixed stud 31a and meshing with two sun gears 38a and 39a having the same pitch diameters and also coaxially mounted for rotation about the axis of the seconds shaft 20a. As before, the sun gear 38a is provided with sixty teeth and is fixed to the inner end of the minutes sleeve 25a and the sun gear 39a is provided with fifty-nine teeth and is fixed to the inner end of a sleeve 40a journaled on the minutes sleeve 25a. Secured to the other end of the sleeve 40a is a large disk 42a having teeth 43a formed on its periphery and adapted to be engaged and held stationary by a locking projection 44a on the lower end of an arm 45a of a lever 46a rotatably mounted upon a fulcrum shaft 47a which is in turn supported by the plates 12a and 13a.

Fixed to the minutes sleeve 25a through a collar 21a is a disk 80a having a single notch 82a in its outer periphery adapted to be engaged by a tooth like projection 83a on the outer end of a lever arm 84a also rotatably supported by the fulcrum shaft 47a. As in the previous modification, the notch 82a is so located with respect to the tooth-like projection 83a that when the latter enters the notch the minutes sleeve 25a is in the zero or sixty minute position, which is the position the sleeve should occupy at the beginning of each normal operating period.

Fixed to the lever arm 84a by an integral plate 86a is a second lever arm 87a journaled on the shaft 47a and having a pin-and-slot connection with a lever 90a also fulcrumed on said shaft 47a and having a stop projection 94a which, when the arms 84a, 87a and 90a are rocked clockwise and the projection 83a has entered the notch 82a, is in the path of the planet arm 34a and stops the latter and seconds shaft 20a at the zero or sixty second position.

The lever arm 45a of lever 46a and the arm 84a are adapted to be operated by an operating

lever 50a including an arm 49a having a pin 66a extending from both sides thereof and operable when the arm 49a is moved clockwise to engage a second arm 67a on the lever 46a and to move the arm 45a clockwise against the force of a spring 48a for the purpose of disengaging the locking projection 44a from the teeth 43a of disk 42a; and the pin 66a being also operable when the lever 50a is moved counterclockwise to engage the underside of lever arm 84a and move the latter counterclockwise against the force of a spring 85a to disengage the projection 83a from the notch 82a.

As in the previous modification, the operating lever 50a includes an upward extending arm 68a having a vertical slot 69a formed therein and receiving a pin 70a carried by the lower end of an arm 71a which is pivoted at its upper end to a fixed pivot pin 75a and is connected intermediate its ends to the armature 73a of a solenoid 74a.

As before, the solenoid 74a is energized at the beginning of a synchronizing period and is de-energized at the end of such period. When the solenoid is energized, the armature 73a is moved to the right as viewed in Fig. 8 thereby moving the operating lever 50a clockwise to effect the releasing of the disk 42a and minutes sleeve 25a and to permit the spring 85a to move the arm 84a clockwise so that the projection 83a engages the rim of the disk 80a and fits within the notch 82a when the disk 80a occupies the zero or sixty minute position. Also, when the solenoid is de-energized the tension spring 77a moves the operating arm 45a counterclockwise to effect operative engagement of the pin 66a with the arm 84a to release the disk 80a and to permit the spring 48a to move the arm 45a counterclockwise to engage and thereby lock the disk 42a against rotation.

At the end of synchronizing periods and during normal operating periods, when the solenoid is deenergized and the disk 42a and fifty-nine tooth sun gear 39a is thereby locked, movement of the planet arm about its axis at the speed of the seconds shaft results in advancing the sixty tooth sun gear 38a and minutes sleeve 25a at the rate of one tooth or $1/60$ of a revolution for each revolution of the planet arm.

According to this modified form of the invention, during synchronizing periods when the solenoid is energized to release the sun gear 39a, the sun gear 38a and minutes sleeve 25a are advanced at the same speed as the seconds shaft due to a frictional connection between the planet pinion and the fixed stud on which it rotates. This frictional connection is provided by means of a spider-like spring element 130 engaging the side of the planet pinion 35a and forcing the same against a disk of friction material 131 located between the pinion and the side of the arm 34a. This frictional connection offers a constant resistance to the rotation of the pinion about its axis; but such resistance is not enough to interfere with the normal rotation of the pinion, under the control of the stationary sun gear and the rotating planet arm, during normal operating periods. However, when the sun gear is released in the manner previously explained, the frictional connection is enough to hold the pinion against rotation about its axis; and, as a consequence, the arm 34a will drive the sun gear 38a through the stationary pinion 35a, at the same speed as the arm 34a. Thus, the rotation of the planet pinion is controlled by the frictional con-

nection during synchronizing periods so as to effect a one-to-one driving connection between the arm 34a and sleeve 25a in the manner just described. This frictional connection takes the place of the gears 55 and 56 and sleeve 60 and disk 61 of the previously described modification.

In Fig. 12 of the drawings, I have shown a diagram illustrating an alternative way of operating one or more secondary clocks of the type shown in either of the previously described modifications, and in controlling the operation of the clocks in accordance with the timed operation of a master clock. In the diagram, the reference character 133 indicates the primary of a transformer 134 which may be connected to the usual alternating current supply. Alternating current will flow from one side of the secondary 135 of the transformer through the wire 136, wire 137, and wires 138 connected in parallel, to the respective motors 15 or 15a, of the secondary clocks depending upon which form of clock is used; and, from the motors the current will flow through wires 139, wire 140, wire 141, and wire 142 back to the other side of the secondary 135. The contacts 143 are a part of a master clock of any suitable construction and are intended to be closed at fifty-nine minutes past each hour to initiate the synchronizing period and to be opened at the sixty minute or zero position to end the synchronizing period and initiate the next normal operating period. When the contacts 143 are closed, current will flow from the secondary 135 through wire 136 and wire 144 to the input side of a half-wave dry-plate rectifier 145 of suitable construction, and from the output side of the rectifier through wire 146, contacts 143, wire 147, and wires 148 connected in parallel to the coils of the solenoids 74 or 74a, as the case may be. The return sides of the solenoids are connected by the wires 139, wire 140, wire 141, and wire 142 to the other side of the secondary 135. As will be apparent to those skilled in this art, current flowing from the rectifier 145 is direct current, and flows as a series of impulses or waves. A condenser 149 in a wire 150 connecting the wires 142 and 147 is provided for smoothing out the D. C. current flow and thereby rendering the same more constant. This construction and operation of a half-wave rectifier combined with a condenser is of course well known to those skilled in this art and requires no further explanation.

In the modified form of secondary clock 10b shown in Figs. 13, 14, 15 and 16, and in the circuit diagram in Fig. 17, I have disclosed an alternative construction of the operating lever 50b and an alternative means for moving the operating lever in response to two separate signals received from the master clock and being of two seconds duration each instead of the one continuous signal of one minute duration disclosed in the two previously described modifications. Other than the structure of the operating lever 50b and the structure and operation of the mechanism, to be described, for moving the lever 50b in response to the two signals, the structure and operation of each of the other elements of the clock 10b is identically the same as the corresponding parts in the modification shown in Figs. 1 to 6, inclusive. Consequently, I will not repeat herein the description of these other elements of the clock 10b except as is required to understand the construction and operation of the elements which have been modified.

The operating lever 50b comprises the arm 49b

carrying the pin 66b which coacts with the arms 67b and 84b to effect locking and unlocking of the disks 61b and 42b and to effect engagement and disengagement of the projection 83b with the disk 88b all in the same manner and for the same purpose as corresponding parts of the previously described modification of Figs. 1 to 6, inclusive. In addition to the arm 49b, the lever 50b also includes an arm 175 having a longitudinal extending slot 176 formed therein and receiving the outer end of a stud or pin 177 carried by the lower end of a lever 178 (see also Fig. 16). The lever 178 is pivoted at its upper end on a fixed fulcrum stud 179 carried by the intermediate support plate 13b and is provided intermediate its ends with an outwardly projecting follower pin 180 operable to engage and be moved by the multiple lobe cam 181. The cam 181 is fixed to a sleeve 182 journaled on the fulcrum shaft 47b and the cam comprises a plurality of similar lobes 183 which are equally spaced circumferentially from one another to provide similar recesses 184 therebetween and are formed on their respective peaks with similar dwell portions 185. A ratchet wheel 186 is also fixed to the sleeve 182 and is operated by a pawl 187 pivoted on the pin 70b which is carried by the lower end of lever arm 71b. Like in the previous modifications, the arm 71b is pivoted at its upper end to a fixed pin 75b and is connected intermediate its ends to a pin 72b carried by the outer end of the armature 73b of the solenoid 74b. A tension spring 190 connects the lower end of the arm 71b and a fixed stud 191 carried by the plate 13b and functions when the solenoid 74b is deenergized to move the arm 71b and pawl 187 to the left as shown in Fig. 13 for the purpose of indexing the ratchet wheel 186 and cam 181 in a counterclockwise direction. A non-return pawl 192 is pivoted on the stud 179 and is held in engagement with the ratchet wheel 186 by a tension spring 193 connecting the pawl 192 and stud 179.

As will be apparent from the foregoing, the pawl 187 is moved to the right as viewed in Fig. 13 by the arm 71b and armature 73b when the solenoid 74b is energized, and is moved to the left by the spring 190 when the solenoid is deenergized. The length of movement of the pawl 187 is such as to advance the ratchet wheel 186 counterclockwise one tooth each time the solenoid is deenergized. In the construction shown the ratchet is provided with twenty-four teeth and the cam 181 with twelve lobes 183. Thus, each time the ratchet wheel 186 is advanced one tooth the cam 181 is moved counterclockwise one half the distance between radial center lines of adjacent lobes 183. The cam is so positioned with respect to the ratchet that at the end of each stroke in an advancing direction of the pawl 187, the pin 180 will be midway of either a dwell portion 185 or midway of a recess portion 184. When the cam 181 moves the pin 180 from a recess 184 to a high dwell point 185 the lever 178 is moved clockwise and thereby also moving through the pin 177 the operating lever 50b in a clockwise direction. When the cam 181 moves so that the pin 180 will occupy a recess 184, the arm 178 is moved counterclockwise under the control of the cam. The force for moving the arm counterclockwise is supplied by the spring 77b and acts through the operating lever 50b and pin 177, as will be apparent.

As set forth in the description of Figs. 1 to 6, inclusive, clockwise movement of the operating lever 50b results in the pin 66b moving the

lever 46b clockwise to release the disk 42b and lock the disk 61b, and in permitting the spring 85b to move the lever 84b into engagement with the disk 80b so as to stop the latter in the sixty minute position when the projection 83b enters the notch 82b, and to move the arm 93b down into the path of the planet arm 34b when the projection 83b enters the notch 82b, for the purpose of stopping the seconds shaft in the sixty second position. Also, counterclockwise movement of the lever 50b results in the pin 66b moving the arms 84b and 93b to release the disk 80b and the planet arm 34b, and results in the spring 47b moving the lever 46b counterclockwise to lock the disk 42b and release the disk 61b.

According to the modified construction of Figs. 13, 14, 15, and 16, the pin 189 occupies a recess 184 during normal operating periods and engages a high dwell point 185 during synchronizing periods. In Fig. 17, I have shown a wiring diagram illustrating how the motors 15b of the clocks 10b are operated by an A. C. current from the usual power and light line and how the operation of the clocks is controlled by a master clock operating at the correct time rate. In the diagram, the contacts 200, 201, 202, and 203 are a part of a master clock of any well known construction and are operated so that the contacts 200 are closed at the sixty minute (60') position of each hour and are opened at fifty-eight minutes and forty seconds (58' 40'') past each hour, the contacts 201 are closed at fifty-eight minutes and forty seconds (58' 40'') past each hour and are opened at the sixty minute (60') position, the contacts 202 are opened at each fifty-eight second (58'') position and are closed at each sixty second (60'') position, and so that the contacts 203 are closed at each fifty-eight second (58'') position and are opened at each sixty second (60'') position.

The primary 204 of the transformer 205 is adapted to be connected to any convenient source of alternating current. When the contacts 200 are closed, A. C. current will flow from a midpoint 206 of the secondary 207 through a wire 208, the contacts 200, wire 209 and the wires 210 connected in parallel, to the motors 15b of the secondary clock; and will flow from the motors through wires 211, wire 212, and wire 213, back to the secondary 207. Thus the motors 15b will be operated by A. C. current through the closed contacts 200 from the beginning of each normal operating period until fifty-eight minutes and forty seconds past each hour when the contacts 200 open. As the contacts 202 remain closed from the beginning of each minute until fifty-eight seconds past each minute, A. C. current will also flow to the motors during the fifty-eight seconds beginning with the fifty-ninth minute. The path of the current flow will be from the secondary 207 through the wire 208, wire 214, closed contacts 202 and wire 215, to the wire 209, and from there through the motors 15b back to the secondary 207, as before. A half-wave rectifier 216 is connected to the secondary 207 by a wire 217, and when the contacts 201 and 203 are both closed, a D. C. current will flow from the output side of the rectifier 216 through a wire 218, contacts 201, wire 219, contacts 203, wire 220, wire 209, wires 210, to the solenoids 74b and from the solenoids through the wires 211, a wire 212, and wire 213 back to the secondary 207. A wire 221 with a condenser 222 therein, connects the wire 219 and the secondary 207 for the pur-

pose of smoothing out or making more uniform the D. C. current.

From the foregoing, it is apparent that the solenoid 74b will be energized for a two-second duration beginning at fifty-eight minutes and fifty-eight seconds past each hour and ending at fifty-nine minutes past each hour, and will be again energized for a two second duration beginning at fifty-nine minutes and fifty-eight seconds past each hour and ending at the zero or sixty minute position. As the contacts 202 are open, when the contacts 203 are closed which is during these two two-second intervals when the solenoids 74b are energized, no A. C. current will flow to the motors 15b during such intervals. This, however, will not materially affect the operation of the motors as the normal inertia of the moving parts will be enough to keep the motors in motion during these two short intervals.

In Figs. 13, 14 and 15 the parts are shown in the positions which they occupy when the solenoid 74b is being energized for the two second duration between fifty-nine minutes and fifty-eight seconds after each hour and the sixty minute or zero position. The armature 73b is shown retracted and the pawl 187 in its right-hand position as viewed in Fig. 13. The pin 180 on the lever 178 is shown as being in engagement with a high dwell point 185 on the cam 181. This is the position it occupies during each synchronizing period. When the solenoid 74b is deenergized, by the opening of contacts 203, and also contacts 201, at the sixty minute position, the spring 190 will move the pawl 187 to the left and index the ratchet 186 and cam 181 to permit the pin 180 to be moved into the next depressed portion 184 which also permits the arm 178 and operating lever 50b to be moved counterclockwise by the spring 77b, to lock the disk 42b and release the disk 61b and to move the arms 84b and 90b counterclockwise to release the disk 80b and the planet arm 34b. The secondary clocks 10b will then operate at their normal rate until the solenoid 74b is again energized and then de-energized at fifty-nine minutes past the hour to index the ratchet 186 and cam 181 so as to move the arm 178 and operating lever 50b clockwise which is the position they occupy during each synchronizing period.

While there have been shown and described and pointed out the fundamental novel features of the invention as applied to a plurality of modifications, it will be understood that various omissions and substitutions and changes in the form and details of the device illustrated and in its operation may be made by those skilled in the art, without departing from the spirit of the invention. It is the intention, therefore, to be limited only as indicated by the scope of the following claims.

What is claimed is:

1. In a clock of the type wherein the minutes member is driven at its regular time rate during normal operating periods by means of a rotating planet arm and a planet pinion rotatably mounted thereon and geared to a pair of coaxially mounted sun gears one of which has a driving connection with the minutes member and the other of which is held stationary during such normal operating periods, the combination of means operable during a synchronizing period occurring between successive normal operating periods for correcting for loss of time and said means including means for releasing the other of said sun gears, means for rotating said pinion

in the same direction as during normal operating periods, but at a definitely slower rate whereby said one sun gear is rotated at a greatly accelerated rate, and means for determining the amount said minutes member is advanced during such synchronizing period.

2. Time keeping apparatus comprising a rotatable time indicating member; mechanism operating at a predetermined definite time rate materially greater than the normal time rate for said member; a planetary gear system connecting said mechanism and said member for rotating the latter at the proper time rate during normal operating periods and comprising a planet arm operatively connected to said mechanism for rotation about a fixed axis, a planet pinion rotatably mounted on said arm and movable therewith along a prescribed orbit, and first and second sun gears mounted, respectively, to rotate about said fixed axis and geared to said pinion, said first sun gear having a driving connection with said member, the number of teeth on said first and second sun gears being so proportioned that with said second gear held stationary, said first gear is advanced at a rate proper to rotate said member at its normal time rate; signal means determining a synchronizing period of relatively short duration occurring at regular time intervals between successive normal operating periods; means for holding said second gear stationary during normal operating periods and for releasing said second gear during synchronizing periods; means for controlling the rotation of said planet pinion to cause said arm to drive said first sun gear at a greatly accelerated rate during synchronizing periods; and stop means operable in response to said signal means and during said synchronizing period for stopping said member upon reaching a predetermined time position and operable to release said member at the beginning of the next succeeding normal operating period.

3. Time keeping apparatus comprising a rotatable seconds indicating member; a rotatable minutes indicating member; mechanism for rotating said seconds member at its normal time rate; a planetary gear system connecting said mechanism and said minutes member for rotating the latter at its normal time rate during normal operating periods and comprising a planet arm operatively connected to said mechanism for rotation about a fixed axis, a planet pinion rotatably mounted on said arm and movable therewith along a prescribed orbit, and first and second sun gears mounted, respectively, to rotate about said fixed axis and geared to said pinion, said first sun gear having a driving connection with said minutes member, the number of teeth on said first and second sun gears being so proportioned that with said second gear held stationary, said first gear is advanced at a rate proper to rotate said minutes member at its normal time rate; signal means determining a synchronizing period of relatively short duration occurring at regular time intervals between successive normal operating periods; means for holding said second sun gear stationary during normal operating periods and for releasing said second gear during synchronizing periods; means for controlling the rotation of said planet pinion to cause said arm to drive said first sun gear at a greatly accelerated rate during synchronizing periods; and stop means operable in response to said signal means and during said synchronizing period for stopping said minutes and seconds

members upon reaching a predetermined time position and operable to release said minutes and seconds members at the beginning of the next succeeding normal operating period.

4. Time keeping apparatus comprising a rotatable minutes indicating member; mechanism including a planetary gear system for rotating said member at its normal time rate and comprising a planet arm rotatable about a fixed axis at the rate of one revolution per minute, a planet pinion rotatably mounted on said arm and movable therewith along a prescribed orbit, first and second sun gears rotatably mounted about said fixed axis and geared to said pinion, said first gear having a driving connection with said minutes member, the number of teeth on said first and second gears being so proportioned that with said second gear held stationary said first gear is advanced at a rate proper to rotate said member at its normal time rate; signal means determining a synchronizing period of relatively short duration occurring at regular time intervals between successive normal operating periods; means for holding said second gear stationary during normal operating periods and for releasing said second gear during synchronizing periods; means for controlling the rotation of said planet pinion to cause said arm to drive said first gear at a greatly accelerated rate during synchronizing periods; and stop means operable in response to said signal means and during said synchronizing period for stopping said arm and said minutes member upon reaching a predetermined time position and operable to release said arm and said member at the beginning of the next succeeding operating period.

5. Time keeping apparatus comprising a time indicating member; mechanism for rotating said member at the normal time rate during normal operating periods and comprising a planet arm rotated about a fixed axis at a definite time rate materially greater than the normal time rate for said member, a planet pinion rotatably mounted on said arm and movable therewith along a prescribed orbit, first and second sun gears mounted for rotation about said fixed axis and geared to said pinion, said first gear having a driving connection with said member, said second gear being held stationary during normal operating periods, the number of teeth on said first and second gears being so proportioned that the first gear is advanced by said arm and pinion during normal operating periods at a rate proper to rotate said member at its normal time rate; and means operable during a synchronizing period occurring between successive normal operating periods to correct for loss of time and to start said time indicating member off at the correct time at the beginning of the next normal operating period and said means comprising means for releasing said second gear, means for rotating said pinion in the same direction as during a normal operating period but at a materially slower rate, and means for stopping said time indicating member upon reaching a predetermined time position and for releasing such member at the beginning of the next normal operating period.

6. Time keeping apparatus comprising a seconds indicating member; means for rotating said member at its normal time rate; a planet arm connected to said member and rotatable therewith about the axis of movement of said member and at the same rate; a planet pinion

rotatably mounted on the outer end of said arm and movable therewith along a prescribed orbit; a rotary minutes member coaxially mounted with respect to said seconds member; a first sun gear fixed to said minutes member and rotatable about its axis and meshing with said pinion; a second sun gear coaxially mounted with said first gear and also meshing with said pinion and being held stationary during normal operating periods; the number of teeth on said two sun gears bearing such a relation that with said second gear held stationary said first gear is rotated one sixtieth of a revolution for each revolution of said arm; and means operable during a synchronizing period occurring between successive normal operating periods to correct for loss of time and comprising means for releasing said second sun gear and for controlling the rotation of said pinion to cause said first gear to rotate at a greatly accelerated rate, and means for stopping said arm and said minutes member upon reaching a predetermined time position and for releasing such arm and minutes member at the beginning of the next succeeding normal operating period.

7. Time keeping apparatus comprising a rotatable time indicating member; mechanism operating at a definite time rate materially greater than the normal time rate for said member; a planetary gear system connecting said mechanism and said member for rotating the latter at its normal time rate during normal operating periods and comprising a planet arm operatively connected to said mechanism for rotation about a fixed axis, a planet pinion rotatably mounted on said arm and movable therewith along a prescribed orbit, and first and second sun gears mounted, respectively, to rotate about said fixed axis and geared to said pinion, said first sun gear having a driving connection with said member, the number of teeth on said first and second sun gears being so proportioned that with said second gear held stationary, said first gear is advanced at a rate proper to rotate said member at its normal time rate; a third gear mounted for rotation about said fixed axis and being of substantially less diameter than said first sun gear; gear means connecting said third gear and said planet pinion; signal means determining a synchronizing period of relatively short duration occurring at regular time intervals between successive normal operating periods; means for holding said second gear stationary during normal operating periods and for releasing said second gear during synchronizing periods; means for holding said third gear against rotation during synchronizing periods and for releasing such gear to permit free rotation thereof during normal operating periods; and stop means operable in response to said signal means and during said synchronizing period for stopping said member upon reaching a predetermined time position and operable to release said member at the beginning of the next succeeding normal operating period.

8. Time keeping apparatus comprising a rotatable time indicating member; mechanism operating at a definite time rate materially greater than the normal time rate for said member; a planetary gear system connecting said mechanism and said member for rotating the latter at its normal time rate during normal operating periods and comprising a planet arm operatively connected to said mechanism for rotation about a fixed axis, a planet pinion

rotatably mounted on said arm and movable therewith along a prescribed orbit, and first and second sun gears mounted, respectively, to rotate about said fixed axis and geared to said pinion, said first sun gear having a driving connection with said member, the number of teeth on said first and second sun gears being so proportioned that with said second gear held stationary, said first gear is advanced at a rate proper to rotate said member at its normal time rate; signal means determining a synchronizing period of relatively short duration occurring at regular time intervals between successive normal operating periods and including means for sending a first signal to initiate said synchronizing period and for sending a second signal to terminate such period; means responsive to said first signal to release said second gear to permit free rotation thereof and responsive to said second signal for locking said second gear against rotation; means for controlling rotation of said planet pinion to cause said arm to drive said first sun gear at a greatly accelerated rate during said synchronizing period; and stop means responsive to said first signal for stopping said time indicating member upon reaching a predetermined time position and responsive to said second signal for releasing said member.

9. A clock comprising a rotatable time indicating member; a motor constructed to operate at a uniform time rate; a planet arm operatively connected to said motor and supported for rotation thereby about a fixed axis and at a time rate materially faster than the normal operating rate for said member; a planet pinion rotatably mounted on said arm and movable therewith through a prescribed orbit; a pair of sun gears mounted for rotation about the same axis as said arm and geared to said pinion; one of said sun gears having a driving connection with said time indicating member and the number of teeth on said one sun gear being so proportioned to the number of teeth on the other of said sun gears that with said other gear held stationary said one gear is rotated by said arm and pinion at a rate correct to drive said member at its regular time rate; means for holding said other gear stationary during normal operating periods; and means for advancing the setting of said time indicating member comprising means for releasing said other sun gear and means for rotating said pinion about its rotary axis in the same direction as it rotates when said other gear is held stationary, but at a definitely slower rate.

10. A clock comprising a rotatable time indicating member; a motor constructed to operate at a uniform time rate; a planet arm operatively connected to said motor and supported for rotation thereby about a fixed axis and at a time rate materially faster than the normal operating rate for said member; a planet pinion rotatably mounted on said arm and movable therewith through a prescribed orbit; a pair of sun gears mounted for rotation about the same axis as said arm and geared to said pinion; one of said sun gears having a driving connection with said time indicating member and the number of teeth on said one sun gear being so proportioned to the number of teeth on the other of said sun gears that with said other gear held stationary said one gear is rotated by said arm and pinion at a rate correct to drive said member at its regular time rate; means for holding said other gear stationary during normal operating periods; and means for changing the setting of said time indicating member.

cating member comprising means for releasing said other sun gear and means for positively rotating said pinion about its rotary axis and at a predetermined rate different from its rate of rotation while said other sun gear is held stationary.

11. A clock comprising a rotatable time indicating member; a motor constructed to operate at a uniform time rate; a planet arm operatively connected to said motor and supported for rotation thereby about a fixed axis and at a time rate materially faster than the normal operating rate for said member; a planet pinion rotatably mounted on said arm and movable therewith through a prescribed orbit; a pair of sun gears mounted for rotation about the same axis as said arm and geared to said pinion; one of said sun gears having a driving connection with said time indicating member and the number of teeth on said one sun gear being so proportioned to the number of teeth on the other of said sun gears that with said other gear held stationary said one gear is rotated by said arm and pinion at a rate correct to drive said member at its regular time rate; means for holding said other gear stationary during normal operating periods; and means for advancing the setting of said time indicating member comprising an electromagnet element operable upon a change in flow of current thereto, means responsive to the operation of said element for releasing said other sun gear and for effecting positive rotation of said pinion about its rotary axis and in the same direction as it rotates when said other gear is held stationary but at a definite slower rate.

12. A clock comprising a rotatable time indicating member; a motor constructed to operate at a uniform time rate; a planet arm operatively connected to said motor and supported for rotation thereby about a fixed axis and at a time rate materially faster than the normal operating rate for said member; a planet pinion rotatably mounted on said arm and movable therewith through a prescribed orbit; a pair of sun gears mounted for rotation about the same axis as said arm and geared to said pinion; one of said sun gears having a driving connection with said time indicating member and the number of teeth on said one sun gear being so proportioned to the number of teeth on the other of said sun gears that with said other gear held stationary said one gear is rotated by said arm and pinion at a rate correct to drive said member at its regular time rate; means for holding said other sun gear stationary during normal operating periods; and means for changing the setting of said time indicating member comprising an electromagnetic element operable upon a change in flow of current thereto, and means responsive to the operation of said element for releasing said other sun gear and for effecting positive rotation of said pinion about its axis and at a predetermined rate different from its rate of rotation while said other sun gear is held stationary.

13. Time keeping apparatus comprising a rotatable time indicating member; mechanism operating at a definite time rate materially greater than the normal time rate for said member; a planetary gear system connecting said mechanism and said member for rotating the latter at its normal time rate during normal operating periods and comprising a planet arm operatively connected to said mechanism for rotation about a fixed axis, a planet pinion rotatably mounted on said arm and movable therewith along a pre-

scribed orbit, and first and second sun gears mounted, respectively, to rotate about said fixed axis and geared to said pinion, said first sun gear having a driving connection with said member, the number of teeth on said first and second sun gears being so proportioned that with said second gear held stationary, said first gear is advanced at a rate proper to rotate said member at its normal time rate; a third gear mounted for rotation about said fixed axis and being of substantially less diameter than said first sun gear; gear means connecting said third gear and said planet pinion; means for holding said second gear stationary during normal operating periods; said third gear being free to rotate during normal operating periods; and means for correcting for loss of time comprising means for releasing said second gear, means for holding said third gear against rotation, and means for stopping said time indicating member upon reaching a predetermined time position.

14. Time keeping apparatus comprising a rotatable time indicating member; mechanism operating at a definite time rate materially greater than the normal time rate for said member; a planetary gear system connecting said mechanism and said member for rotating the latter at its normal time rate during normal operating periods and comprising a planet arm operatively connected to said mechanism for rotation about a fixed axis, a planet pinion rotatably mounted on said arm and movable therewith along a prescribed orbit, and first and second sun gears mounted, respectively, to rotate about said fixed axis and geared to said pinion, said first sun gear having a driving connection with said member, the number of teeth on said first and second sun gears being so proportioned that with said second gear held stationary, said first gear is advanced at a rate proper to rotate said member at its normal time rate; a third gear mounted for rotation about said fixed axis and being of substantially less diameter than said first sun gear; gear means connecting said third gear and said planet pinion; means for holding said second gear stationary during normal operating periods; said third gear being free to rotate during normal operating periods; and means for advancing the setting of said time indicating member comprising means for releasing said second gear and means for holding said third gear against rotation.

15. Time keeping apparatus comprising a driving motor constructed to operate at a uniform time rate; a time indicating member; adjustable motion transmitting mechanism connecting said driving motor and said member and operable in a first adjusted condition to effect operation of said member at its normal time rate, and operable in a second adjusted condition to effect operation of said member at a greatly accelerated rate; and control means including signal means determining a synchronizing period of relatively short duration and occurring at regular time intervals between successive normal operating periods and including means for sending a first signal to initiate each synchronizing period and for sending a second signal to terminate such period, means responsive to said first signal for adjusting said mechanism to operate in its said first adjusted position and responsive to said second signal for adjusting said mechanism to operate in its said second adjusted position, and means operated by said signal responsive means for stopping said time indicating

21

member upon reaching a position indicating the beginning of the next normal operating period and for releasing said member at the beginning of said next normal operating period.

16. In time keeping apparatus a driving motor; a seconds indicating member operated at its normal time rate by said motor; a minutes indicating member; motion transmitting mechanism connecting said motor and said minutes member and being constructed with two conditions of adjustment, one of which provides for driving said minutes member at its normal time rate and the other of which provides for driving the minutes member at a rate materially faster than normal; means for operating said mechanism in its said other condition of adjustment during a synchronizing period of predetermined duration and for changing said mechanism to operate in its said

22

one condition of adjustment at the end of said synchronizing period; a first stop element movable between an inactive position and an active position where said minutes member is stopped thereby upon reaching a selected time position; a second stop element movable between an inactive position and an active position where said seconds member is stopped thereby upon reaching a selected time position; means for moving said first element into its said active position at the start of the synchronizing period and for afterwards moving said second element into its said active position and concurrently with the stopping of said minutes member; and means for returning both said elements to their inactive positions at the end of said synchronizing period.

FREDERICK Q. RAST.
